SEALING MECHANISM FOR WRAPPING MACHINES

Alfred R. Fuchs, Kansas City, Mo.

Application April 3, 1948, Serial No. 18,745

24 Claims. (Cl. 154—42)

1

My invention relates to wrapping machines, and more particularly to a sealing mechanism for wrapping machines.

In machines for wrapping and sealing packages, such as packages of bread, in which a paraffin paper or similar wrapper is sealed by application of heat thereto, followed by cooling thereof in some manner, difficulty has been experienced with sealing the packages effectively without the use of expensive cooling equipment to refrigerate the seals of the packages to a low temperature. This has been largely due to the fact that either the conveying means, that was utilized for carrying the wrapped bread from the means for wrapping the same and applying heat to the wrappers thereof to melt the paraffin used for sealing the packages, was of such a character that it produced no cooling whatsoever of the seals of the packages, or that the cooling means that was used was slidably engaged by the wrapped packages so that there was relative sliding movement between the engaging surface of the wrapped package and the cooling member, or members, which would tend to disarrange the folded and overlapped layers of paraffin paper forming the closure means of the package, unless a very low temperature was provided at the surface of the cooling means, such as would instantaneously cool the paraffin, or similar material, forming the sealing means. In fact, it has been necessary to produce such a low temperature to avoid sticking of the packages to stationary cooling members, that ice, or frost, had to be formed on these, which would make these stationary sealing members have a surface that was of a character that there would be very little friction existing between the package and these stationary members, to thus avoid the adherence of the sheet material of the wrapping to the stationary means as it moved along the same and prevent a disarrangement or partial unwrapping of the package due to sticking of the package to the cooling members.

In the case of the conveying means ordinarily utilized for carrying the wrapped bread from the hot sealing plates to the conveyor, or other means, transporting the same to the point of packing the sealed packages in suitable boxes, or containers, this conveying means has ordinarily been made in such a way that it either moved the bread forcibly from a surface that was stationary, or else the conveying means was of a belt-like, or similar character, that merely held the package closed while the seals were expected to cool, and was of such a character that

2

it conveyed little or no heat away from the packages and contacted the same part of the package throughout its travel on the conveying means.

5 It is the principal purpose of my invention to avoid the difficulties and objections existing in either the use of the conveying means above referred to, or the refrigerated cooling means that is necessary to form ice or frost on cooling plates, 10 or other stationary cooling members, by providing combined heat conducting and dissipating, and conveying means for the wrapped packages, thus eliminating much expensive equipment, and at the same time providing heat conducting 15 means that successively engage the surface of the packages that have to be cooled, so that these heat conducting means engage any given area of the package that must be cooled one after another, to thus each conduct some of the heat 20 in the package away from the package to dissipate the same through heat conducting bodies of relatively large mass, such as the metallic framework of the machine, or other heat dissipating means that can be provided especially for 25 that purpose.

Under ordinary temperature conditions, in places in which the wrapping machines would be located, such as in bakeries, it is only necessary to utilize the framework of the machine and of the conveying means to dissipate the heat, so that it will be carried away from the packages sufficiently that these will seal without any danger of becoming unwrapped upon passing through the conveying means. In instances 30 where extremely high temperatures are encountered, due to climatic conditions, or due to local conditions in the room in which the machine may be located, cooling means can be utilized for transferring the heat from the package contacting members to said cooling means, and while it is necessary in the case of stationary sealing plates, to utilize direct expansion refrigerating means to cool the packages, only a cool liquid, such as ordinary tap water obtained from the 35 usual city water system, is necessary even where high temperatures are encountered in the room in which the wrapping machine is located, in my improved apparatus, to cool the members that contact the package sufficiently to thoroughly 40 seal the package and keep it sealed.

45 This is due to the fact that a large number of rotatable cooling members of heat conducting material are ordinarily utilized in carrying out my invention, to withdraw the heat from the 50 seals of the packages, said rotatable cooling

members being so mounted and engaging with the packages in such a way that the contacting surfaces of the heat conducting members and the packages are always moving at substantially the same speed, and thus a different surface of the heat conducting member is constantly engaging the package, and different heat conducting members successively engage the same part of the surface of the package. Thus there is no rubbing or brushing action exerted by the package on engaging the cooling members, such as tends to disarrange the package, and furthermore the successive cooling members act as cool pressure rollers, or sealing rollers, that exert a rolling sealing pressure on the seals of the packages that is only sufficient to press the seals together properly, without exerting any undue pressure on the contents of the package.

My invention also contemplates the use of heating devices for the seals, of a similar character to the cooling devices above referred to, the sealing means comprising heated rollers instead of stationary heating plates, as is now customary, with which the seals of the packages successively engage to seal the packages, thus making it possible to convey the packages through the sealing means at a constant rate of speed with a continuous forward movement, instead of a step by step, or intermittent movement, as is now customary.

Furthermore my invention contemplates the use not only of solid heat conducting rollers engaging the packages in a manner that the contacting surfaces of the rollers and the packages move at substantially the same speed, but also such rollers contacting the packages in this manner that have cooling means within the same, such as a cooling liquid of the character above referred to. Of course, if desired, it is possible to cut down the number of the rotating cooling members to a very small number and eliminate most of the conveyor, if these rotating cooling members are cooled by direct expansion refrigerating means, but from an economy standpoint, this would not be particularly desirable, as it would require the use of refrigerating apparatus, although it would produce a better seal, without the necessity of maintaining frost on the rollers, than would be possible with plates that had frost, or ice, thereon, because of the fact that the contacting faces of the package and the rollers would be always moving at the same speed and there would be no relative sliding movement of the same that might disarrange or open up the seal, or seals, of the package.

In a most general aspect, my invention comprises a plurality of rollers of heat conducting material and means for moving wrapped packages in heat transfer relation to said rollers, whether the heat is transferred from the rollers to the packages or from the packages to the rollers, and, preferably, for packages, such as wrapped bread, the rollers comprise two series of rollers that rotate about substantially vertical axes, and a series of rollers that rotate about horizontal axes, contacting the packages, preferably, simultaneously.

The rollers, in the simplest embodiment of the invention, are merely mounted to rotate on fixed axes, although it is necessary, because of the different lengths of loaves of bread that are wrapped, to provide adjustment of the rollers rotating on vertical axes toward and away from each other, and also it is desirable to provide yielding means for urging the rollers that are

arranged to rotate on vertical axes toward the package to exert a slight spring pressure on the package and on the seals to provide a sealing contact between the different layers of the paraffin paper, or other heat sealing sheet material, ordinarily used for wrapping packages, such as bread, at least one set of rollers rotating on vertical axes thus not having the axes actually entirely fixed, but having a slight yielding movement for this purpose.

My invention also contemplates the use of a plurality of rollers that are interconnected, so that the same are mounted to rotate about axes that constantly change, the entire series of rollers being carried along in a similar manner to a belt or chain conveyor, so that half of the rollers are always out of contact with the bread packages, or similar packages, and substantially half thereof are in heat transfer relation to a heat dissipating or cooling means, so that the rollers will be constantly cooled and cool rollers presented to the packages to contact therewith, the conveying means being so arranged that the coolest rollers will engage the packages when the same are the hottest. However, the series of rollers will successively engage the packages as the same move along with the conveying means, and the conveying means is moved as a whole by the packages, and not the packages by the conveying means.

If desired, means can be utilized engaging the packages to move the same along into engagement with the successive rollers in any form of the apparatus referred to, but in the simplest form of apparatus, it has been found to be desirable to utilize the action of gravity on the packages to carry the same forward in contact with the successive rollers, thus requiring no additional power or mechanism, except the rollers themselves, to both convey the packages to a desired point and to cool the same.

Other objects and advantages of my invention will appear as the description of the accompanying drawings proceeds. I desire to have it understood, however, that I do not intend to limit myself to the particular details shown or described, except as defined in the claims.

In the drawings:

Fig. 1 is a top plan view of my improved sealing means, a portion of the wrapping machine to which my invention has been applied being also shown.

Fig. 14 is a fragmentary top plan view of a further modification of the invention.

Fig. 15 is a fragmentary view partly in elevation and partly in vertical section of one of the vertical heating rollers utilized in the form of the invention shown in Fig. 14, and

Fig. 16 is a view similar to Fig. 15 of the horizontal heating rollers utilized in the form of the invention shown in Fig. 15.

Referring in detail to the drawings, in Figs. 1 and 2 is shown a fragmentary portion of a wrapping machine of a well known conventional form, showing a plurality of packages in the form of loaves of wrapped bread 20 thereon, which have been carried by means of a conveyor having the side chains 21, and pusher members 22 thereon, into engagement with suitable vertically extending heating plates 23 and a horizontally extending heating plate 24, which are mounted on the wrapping machine in any suitable manner, the plates 23 being adjustable relative to each other to vary the spacing between the same by means of the adjusting means indicated generally by the numeral 25. One of the wrapped packages, or wrapped loaves of bread, 20 shown on the machine, in Fig. 1, is not yet in engagement with the heating plates 23 and 24, and serves to push the loaves of bread, or other wrapped packages 20, that are in engagement with the heating plates in a step by step action over the heating plates and out of contact therewith as successive loaves 20 move into position from the left in Fig. 1, the loaves moving out of engagement with the heating plates at the right hand end of the wrapping machine.

The conveying means may be of any desired character, but is shown as being of a type in which the pusher members 22 are so mounted that the same swing from a vertical to a horizontal position after the same reach the right hand end of the conveyor, passing out of engagement with each loaf of bread, or other package, that has been wrapped by the machine as the wrapped loaves, or packages, approach the heating plates 23 and 24, so that the loaves are only moved by the conveyor continuously until the same reach a position in engagement with the heating plates 23 and 24, and remain in position on these heating plates until a succeeding wrapped loaf, or package, is brought up by the next pusher member 22. The loaves thus have an intermittent movement, step by step, while in contact with the heater plates, being stationary in contact with said heater plates for intervals determined by the intervals between the pushing movements exerted by the succeeding loaves of bread being brought up by the conveyor having the pusher members 22. The loaves are thus discharged from the heating means, thus provided, at regular intervals after being in contact with said heater members definite periods of time.

A very high heat is utilized, ordinarily, for melting the paraffin coating on the sheet material that is used to wrap the bread, or to heat any other sheet material that can be caused to adhere together by means of application of heat thereto. As a result the entire wrapping of the package is very hot when it leaves the wrapping machine,

and as the congealing of the paraffin with the layers of sheet material in contact with each other is necessary to seal the package, improper sealing of the package and disarrangement of the sealing portions of the package will take place after the same leaves the wrapping machine, unless the paraffin, or similar material, with which the sheet is impregnated, or coated, is cooled sufficiently to cause the plies that form the seal to be sealed to each other before any extensive handling of the package, or other action thereon, that might disarrange or break open the seals, takes place.

While sometimes the surrounding atmosphere in the room in which the wrapping machine is located is sufficient to produce this sealing, if the plies are merely held together by any suitable means, such as conveying means, carrying the packages away from the wrapping machine, it has been found necessary under hot weather conditions in many localities to provide refrigerated plates having frost thereon for cooling the packages, to accomplish this sealing action before the seals might become disarranged and become ineffective. One of the defects existing in both the heating plates and such cooling plates is that there is a relative sliding movement between the contacting portions of the package and the plates, which, of course, has a tendency to brush the plies of sheet material forming the wrapping, in such a manner as to be moved out of their folded and overlapped position. The character of the contents of the package resists this to a certain extent, and while the heating plates are lubricated to some extent by the paraffin that is constantly being melted thereon, that comes off the paraffin paper wrapping that is heated by the plates, the cooling plates have a tendency to cause the packages to adhere thereto, unless these are also lubricated, and the only lubricating means, or friction reducing means that has been successfully used for this purpose has been frost or ice, which slickens the surface of the plates so that the packages will slide thereover without being disarranged to any appreciable extent. However, the provision of such cooling plates involves a great amount of expense and much additional equipment that would not otherwise be necessary in a wrapping machine.

The sealing, in my improvement on a wrapping machine, is accomplished by cooling the packages without sliding the same over or in contact with cooling plates, or other stationary cooling members. By utilizing a rolling contact between the cooling members and the packages, both on the ends and on the bottom thereof, all necessity for any lubricating means is avoided, and as the actual cooling of the packages to cause the paraffin, for example, to congeal to seal the packages, does not require any temperature below the ordinary atmospheric temperature, a lower temperature being only necessary because of the sliding contact between the packages and the cooling members in apparatus now in use, all expensive refrigerating apparatus can be eliminated. My cooling apparatus constitutes combined cooling and conveying means and is utilized to carry the wrapped packages from the wrapping machine to conveying means ordinarily provided in bakeries, for carrying the wrapped bread to packing or loading stations.

Said apparatus comprises a frame of any desired character, but being shown as having longitudinally extending frame members 26, which are connected by transversely extending

frame members 27 at opposite ends thereof to form a rectangular bottom frame for the device, said longitudinally extending frame members 26 being mounted at one end thereof on adjustable legs 28 and at the other end thereof on hinge-like members 29 that are mounted on a portion of the frame 38 of the wrapping machine. Preferably, the legs 28 are so adjusted that the frame members 26 decline from the wrapping machine to the conveying apparatus 31, upon which the packages are discharged to be carried away to suitable loading or packing stations, for a purpose to be described below. The stationary framework of the cooling and conveying means further comprises vertically extending frame members, or standards, 32 and 33, which are connected by means of horizontally extending upper transverse frame members 34 and 35. The frame members 34 are, preferably, made in the form of angles, but the frame member 35 may be merely a bar-like member.

Mounted on the transversely extending top members 34 of the frame are rollers 36, which are carried by transverse members 37 provided on end members 38 of a pair of longitudinally extending frames having the longitudinally extending top frame members 39 and the longitudinally extending bottom members 40 connecting the frame members 38, the members 40 being detachably mounted on the members 38 and the members 39 being, preferably, made integral with the members 38, any suitable means for detachably connecting the members 38 and 40 being provided, such as the bolts 41 passing through ears 49 on said members 40. The members 39 and 40 are, preferably, provided with spaced aligning bearings of a suitable character, for the roller members 42 of heat conducting material. Said rollers 42 are shown in the drawings as being provided with a ball bearing mounting on the lower longitudinal frame members 40, and an ordinary anti-friction bearing mounting on the upper longitudinal frame members 39, said rollers, preferably, having depending integral centering projections 43 thereon that are mounted in the sockets 44, but do not extend to the bottoms of said sockets, and suitable races being provided for the bearing balls 45 in the bottom end portions of the rollers 42 and in said members 40, to provide a ball thrust bearing for said rollers 42 at their lower ends. The members 39 are shown as being provided with bearing sockets 46 that receive the reduced upper ends 47 of the rollers 42, and a sleeve-like member of anti-friction material 48 being provided between the reduced end 47 and the wall of the socket 46.

One of the frames above described is, preferably, fixed in position by means of a bracket member 49 that connects the lower longitudinal member 40 of said frame with the vertically extending frame member 33. The frame members are made substantially identical, as far as the mounting of the end members on the transverse frame members 34 is concerned, because it is desirable to standardize the parts, and it may be desirable to adjust both frames instead of only one to adjust the spacing of the one set of rollers 42 from the other set. The other frame member 39 is provided with an upwardly projecting housing 50, which is provided with a channel 50' therein forming a passage that has an end wall 51, which a stop comprising a washer fixed on a screw 53 is adapted to engage. The screw 53 engages an internally threaded opening in a

bracket member 54 mounted on the one vertical frame member 33 and is provided with any suitable means for turning the same, such as the crank 55.

It will be obvious that by turning the screw by means of the handle 55 the stop 52 can be adjusted in its position to limit the movement of the member 39 having the housing 50 thereon toward the member 39 on the other side of the device. Said stop member 52 is, preferably, so adjusted that the distance between the opposed rollers 42 at their nearest points will be slightly less than the length of the wrapped loaf of bread, or package, but not so much less that the loaf will be unduly compressed in passing between the rollers when in such position that the stop 52 is engaged by the wall 51 on the housing 50 provided on the member 39. It is desirable that a yielding pressure of the rollers on the ends of the packages be exerted, to get the most satisfactory sealing and cooling action of the rollers 42. This can be obtained in any desired manner, one means of accomplishing this being the relatively weak coil tension springs 56, which connect the transverse members 37 of the longitudinally extending frames carrying the rollers 42 at opposite ends of the device. Due to the provision of the springs 56, the longitudinally extending frame that is provided with the adjustable stop member 52 is held in position with said stop member 52 in engagement with the end wall 51 provided on the frame until a wrapped package, or wrapped loaf of bread, engages the rollers, whereupon the bread forces the rollers apart, thus providing a close contact between both sets of rollers and the loaves of bread, but without unduly compressing and damaging the fresh loaves, this being particularly important in connection with sliced bread. Obviously both frames can be made adjustable instead of only one, if this is found to be preferable.

The longitudinally extending frame members 26 are made in the form of angles, as will be evident from Fig. 3, and each has a bar-like member 57 secured thereto by welding, or in any other similar manner, said bar-like member being provided with sockets 58 that align with openings 59 in the member 26, a bearing sleeve 60 being mounted in each of said openings and extending into said sockets, in which are mounted roller bearings 61 that support the reduced end portions 62 of the rollers 63 that are made of heat conducting material. The bottoms of the packages engage the rollers 63, as will be obvious from Fig. 4, and the transverse frame members 34 and 35 have links 64 and 65 pivotally connected therewith, respectively, and pivotally connected with a bar-like member 66, which may be pivotally connected with a similar bar-like member 66' by means of a link 67, said bar-like member 66' being frequently provided for engagement with the tops of the loaves of bread, or other packages, passing through the wrapping machine, and the bar like member 66 engaging the tops of the loaves of bread, or packages 28, that engage the rollers 63 of the conveying and cooling device that I have provided. The wrapped loaves of bread, or packages, are thus held in intimate engagement with the successive rollers 63 that the same engage, and in intimate engagement with the successive rollers 42 that the same engage.

Due to the provision of anti-friction bearings for the rollers shown in the drawings, said rollers 63 and 42 will rotate very readily upon engage-

ment of the wrapped packages therewith, and due to the downward inclination of the members 26 away from the wrapping machine toward the conveyor 31, there will be little if any pushing action of one loaf of bread on another necessary to cause the loaves to move over the roller members 63 and into successive engagement with the roller members 42, after the same pass from the heating plates of the wrapping machine. The angle of the members 26 is, preferably, so adjusted that the tendency will be for the loaves to travel by gravity down the inclination of the roller conveyor thus provided. Due to this tendency there will be no tendency for the bread to become compressed because of the pushing action of one loaf of bread on another in moving through the cooling and conveying apparatus I have provided. While the loaves may move by gravity through the entire cooling and conveying means after once being entirely positioned thereon, it is not desirable to have the members 26 at such a steep inclination that the loaves will move rapidly through the cooling and conveying apparatus, as it is desirable that each succeeding roller 42 and each succeeding roller 63 have long enough contact with each of the packages that it will extract considerable heat therefrom.

The rate of travel down the inclined conveying means can be controlled so as to maintain the wrapped packages in substantially side by side relation on the rollers, by adjustment of the inclination of the rollers 26 and the braking action exerted by the member 66.

Instead of merely relying upon the dissipation of heat through the mass of metal constituting the rollers and the frame of the machine, means may be provided for cooling the rollers, as shown in Fig. 6. The frame members are provided with longitudinally extending members 139 and 140 which correspond to the members 39 and 40 described in connection with Figs. 1 to 5, inclusive, and the vertically extending members 138, which correspond substantially to the members 38 of the previously described frames. Said frames 138 may be similarly mounted as are the frame members 38 shown in Figs. 1 to 5, inclusive, on the frame members 34, and may be adjusted in a similar manner to that described in the form of the invention shown in Figs. 1 to 5, inclusive.

Each of the rollers 142 is mounted similarly to the rollers 42 shown in Figs. 1, 2 and 3, but instead of being solid, said rollers are each, preferably, provided with a longitudinal passage 79 therein for a cooling medium. Any suitable means may be provided for feeding the cooling medium into said passages and passing the same out of the same at the lower ends thereof. In the drawings, a flexible tubular member 71 is shown, which has a coupling 72 thereon for connecting the same with a nipple 73 extending upwardly from the longitudinally extending conduit 74, which is provided with branch conduits 75, which extend into the passages 70. A suitable anti-friction bearing sleeve 76 may be provided on each of the tubular members 75 to provide for ready rotation of the rollers 142 relative to the branches 75 of said conduit 74. A discharge passage 77 is provided at the bottom end of each of said rollers 142, in which a nipple 78 is mounted that extends into one of the liquid passages 79 provided in the member 140. The rollers 142 are mounted in a similar manner to the rollers 42 on the ball bearings 45.

Mounted below the member 140 is a pan-like

member 80, into which the liquid passing from the discharge passages 79 passes. Said pan-like member is, preferably, provided with an overflow pipe 81 to maintain a predetermined level 5 of liquid therein so that the rollers 63, which are the same as described in connection with Figs. 1 to 5, inclusive, will be partially immersed in the liquid 82 that collects in said pan-like member, said liquid discharging onto the rollers at the ends thereof from the passages 79 to pass into the pan-like member 80. The nipples 78 are freely rotatably mounted in the openings 79 and are, preferably, made of anti-friction metal. It will be obvious that the cooling liquid will pass 15 in through the inlet tube 71 and be discharged by means of the longitudinally extending conduit 74 to the interior of the various rollers 142, flowing downwardly through the passages 70 from which the liquid will be discharged into the pan 80 and from that will pass outwardly 20 through the discharge conduit 81. The liquid can be either cooled and recirculated, as would be the case with ice water or brine, or merely tap water could be utilized, which would cool the rollers to the desired extent. Any small amount 25 of moisture that would be on the faces of the rollers that would contact the wrapped packages would not be harmful, as the same would quickly evaporate off the packages and would aid in cooling the seals thereof.

Instead of providing the rollers 63, as shown in Fig. 6, rollers 163 can be provided to cooperate with the rollers 142, as shown in Fig. 7, the rollers 142 being supplied with the cooling liquid 35 in the same manner as previously described in connection with Fig. 6, and being mounted in the same manner as previously described. The rollers 163 are mounted in the frame members 126, which are the same as the frame members 26, previously described, except that the bar-like members 157, which are similar to the members 57, previously described, are provided with openings 30 therein, into which the tubular members or nipples 83 of any anti-friction metal extend. It 40 is, of course, to be understood that a similar mounting is provided at both ends of the rollers 163. The tubular member 83 is, preferably, made of anti-friction metal and each tubular member is connected with the longitudinally extending 45 conduit 84, which is similar to the conduit 74, the tubular members 83 constituting branches of said conduit 84. The conduit 84 is supplied with cooling liquid through a flexible tubular member 85 connected by means of a coupling 86, with 50 a nipple 87 that extends to said tubular member 84, said tubular members 74 and 84 thus constituting manifolds for supplying the liquid to the rollers 142 and 163. Any suitable means can be 55 provided for collecting and carrying away the liquid from the tubular members 163, the liquid passing out of the discharge passages 79 from the rollers 142, preferably, passing into a pan-like member 88, from which a discharge pipe 89 extends. The liquid passing from the rollers 60 142 will, of course, engage the outer surface of the rollers 163 when passing through the passages 79, but there will be little, if any, of the liquid thus discharged come in contact with the package, because of the fact that the portions 65 of the rollers 163 that engage the wrapped package 26 will not be in alignment with the passages 79. If the cooling liquid used is brine or ice water, suitable means may be provided for recirculating the same and for cooling the same. 70 75 If the cooling liquid is merely tap water, which

is ordinarily sufficient for cooling rollers such as are provided herein, the water collected in the pan 88 and passing through the rollers 163 can be discharged and not re-used.

In the forms of the invention described above the rollers all rotate about fixed axes. This is not necessary, however, and it is sometimes desirable to rotate the rollers about axes that constantly travel. Such an arrangement is shown in Figs. 8 and 10, the rollers 263, which are the same in construction as the rollers 63, being solid, preferably, are connected together by means of links 90 at the opposite ends thereof forming a roller conveyor in which the rollers travel or roll in a continuous series over a plate 91 of conducting material underlying the same, the packages 20 resting on said rollers 263 in a similar manner to that in which the same rest on the rollers 63. No other guiding means for the rollers 263 need be provided, as the links 90 will hold the same in parallelism and the end walls 92 of the plate-like member 91 will act as guiding means to maintain the chain-like series of rollers in proper alignment with each other and with the remainder of the conveying means, so as to properly cooperate therewith. The rollers 263 being made of metal or similar conducting material, will absorb heat from the seals of the packages 20, and will transfer the heat to the heavy metal plate 91, which is connected in any suitable manner with the frame of the machine, so that the heat will be dissipated throughout the machine, said rollers being thus gradually cooled as the same roll over the plate 91. Furthermore the rollers will be traveling, without rotating, in the air on the underside of the plate 91 to be further cooled, only part of the rollers being in contact with packages at one time, at least half thereof being out of contact with said packages at all times. The links 90 are, of course, connected with the rollers 263 by means of pivot members 93, provided on said rollers 263, any suitable bearing structure to reduce friction being provided as may be desirable.

The vertically extending rollers 242 correspond to the rollers 42, but are connected together to form a continuously connected chain or linked series of said rollers, by means of the links 94 operating over guide wheels, which may be referred to as sprocket wheels 95, said rollers each engaging in one of the partly cylindrical recesses 96 provided in said sprocket wheels to support the same and guide the same in their movements as the same travel in a continuous connected series along with the packages that pass between the two oppositely arranged series of said rollers 242, said rollers being, of course, arranged at opposite ends of the package in the same manner as the rollers 42, and mounted on frame members that are similar to those carrying the rollers 42, so that said series of rollers will be adjustable toward and away from each other and will yieldingly press toward each other to exert a good contact on the wrapped loaf of bread or other package passing along between the same. Said rollers will travel in the same direction as the wrapped loaves of bread or other packages traveling along on the rollers 263, rolling along on a heavy metallic guide plate 239, serving both as a longitudinal frame member and as a guide rail for said rollers, having a lip or flange 243 thereon, along the bottom edge thereof with which the bottom ends of the rollers 242 engage. A supporting rail or plate 97 is also provided for the chain-like series of connected

rollers, being supported from the frame member 239 by means of the brackets 98.

The sprocket wheels 95 are, preferably, mounted on suitable bearing brackets 99, provided on the frame members 239, rotating freely in bearings in said brackets, the sprocket members 95 having stub shaft portions 100 projecting downwardly therefrom into the lower bearing bracket, which may have a rounded end 101 to facilitate assembly of said shaft in said bearing, while the upper end portion of each of said sprockets 95 has a stub shaft 102 projecting therefrom, which is provided with a sleeve of anti-friction metal 103, that is mounted in the bearing 104 provided on the bearing bracket 99.

The particular mounting of the sprocket members 95 is not of importance to the invention, except that these should be mounted to rotate freely about axes parallel to the axes of rotation of the roller members 242. As the rollers 242 will contact the plate-like members 239 constituting the adjustable frame members corresponding to the frames made up of the members 138, 139 and 140 in the form of the invention shown in Figs. 1 to 5, inclusive, substantially the whole of the time that the same are in engagement with the seals of the packages passing between the opposed sets of rollers 242, the heat of the seals will be transferred to said rollers 242 and from said rollers to the plate-like members 239, and from these to the frame of the machine. The heat from the seals will thus be dissipated through the mass of metal thus provided, to maintain the temperature of the rollers and of the seals such that the same will be cooled sufficiently to maintain the same sealed and prevent any disarrangement thereof, which might otherwise occur.

If it should be found to be impossible to dissipate sufficient of the heat through the frame of the machine by the arrangement of the invention shown in Figs. 8 and 10, the construction shown in Figs. 9 and 11 can be used, in which, instead of the heavy metallic plate-like members 91 and 239, means is provided for cooling the rollers 242 and 263 comprising liquid cooled walls with which said rollers have rolling contact, in a similar manner to that in which the same contact the solid metallic walls of the plate-like members 91 and 239. Such walls may be made in any suitable manner to provide a liquid chamber 105 adjacent each set of rollers 242, said chamber being made up of a guide plate 106, as shown in Fig. 11, having the lip 107 thereon, with which the rollers 242 engage to guide the same, and having longitudinal flanges 108 thereon, with which the flanges 109 of a similar plate 110 engage to clamp the compressible packing material 111 therebetween when the fastening elements 112 are tightened up, each of said members 106 and 110, of course, having similarly flanged end walls that close the ends of the chamber. Thus a liquid chamber 105 is provided for cooling the wall 106, with which the rollers 242 engage at each side of the machine, and obviously said member 106 and 110 that form said water chambers can constitute movable frame members corresponding to the frames in the form of the invention shown in Figs. 1 to 5, inclusive, made up of the members 138, 139 and 140. Any suitable means for supplying the cooling liquid to the chambers 105 may be provided, the inlet pipe 113 only being shown in Fig. 11 of the drawings. However, it will be obvious that by suitable hose or flexible pipe connections, liquid can be

circulated lengthwise of the chamber 105, or vertically thereof, as may be preferred.

The rollers 263 can be similarly cooled by means of rolling contact with the top surface of a plate-like member 114 cooperating with a similar plate-like member 115 having, respectively, the flanges 116 and 117 thereon, clamping between them the compressible gasket member 118 when the fastening elements 119 are tightened up to provide a liquid chamber 120 therebetween. The housing made up of the flanged members 114 and 115 can be supplied with cooling liquid in any suitable manner, as through inlet and outlet pipes, the inlet pipe 121 only being shown in the drawings, these being disposed in such a manner as to obtain flow of liquid lengthwise of the chamber 120 or in any other manner desired. While the liquid that would be ordinarily used, and would ordinarily be satisfactory for cooling the plate-like members 106 and 114, would be ordinary tap water, brine or ice water can be utilized, and any suitable means can be utilized for cooling said brine or ice water and for circulating it between the cooling means and the cooling liquid chambers 105 and 120.

In Figs. 14, 15 and 16 my invention is shown as being applied to both the means for heating and for cooling the seals to obtain the sealing action of the wrappers made of paraffin paper, or similar material, that will seal wrapped packages by first contacting the paper that has been properly folded to enclose the package with heating means and then with cooling means. The cooling means shown is the same as that shown in Figs. 1 to 5, inclusive, in that it includes the solid vertically extending rollers 42 and the solid horizontally extending rollers 63, the rollers 42 being mounted on the frame members having the longitudinally extending members 39 and 40, such as previously described, which may be adjustable toward and away from each other by adjustment of the headed pins 122 carried by said frame members 39 in the slots 123 provided in the transversely extending frame member 34', which corresponds to the frame member 34. Instead of providing the pusher members that leave the packages before the same reach the cooling apparatus, as shown in Figs. 1 to 5, inclusive, the pusher members 22, which are mounted between the sprocket chains 21, engage the individual wrapped loaves or packages 20, until the same reach approximately the end of the cooling apparatus made up of the rollers 42 and 63, as will be obvious from Fig. 14, the sprocket chains being driven by means of the shaft 124, which is driven in any suitable manner from the main drive shaft of the wrapping machine. It will be noted that the lower set of pusher members 22 are in vertical position to push the packages 20 toward the right in Fig. 14 in spaced relation to each other, and that the upper pusher members 22 have moved to the horizontal position that these ordinarily assume in wrapping machines of this character during their travel back to the point where the same first engage with said packages after the wrapping material has been wrapped around the same and folded. The conveyor thus provided, made up of the sprocket chains 21 and pusher members 22, will thus continuously move the packages 20 from left to right, as viewed in Fig. 14, first in engagement with the heating apparatus, which will be described below, and then in engagement with the cooling apparatus, causing rotation of each roller 42 and of each roller 63 as the packages are gradually moved along by

the conveying means into engagement with successive rollers.

The heating apparatus for the folded wrapping material enclosing the loaves of bread or similar articles, that are to be wrapped in sealed packages, preferably, comprises a series of freely rotatable horizontal and vertical rollers 127 and 128, respectively. Said rollers are mounted in a similar manner to the rollers 63 and 42. The rollers 128 being rotatably mounted in the frame members 339 and 340, corresponding to the frame members 39 and 40 for the cooling rollers and, preferably, forming extensions thereof, and the rollers 127 being mounted in the frame members 326 in a similar manner to that in which the rollers 63 are mounted in the frame members 26, said frame members 326, preferably, constituting extensions of the frame members 26, the frame members 26 and 326, and the frame members 339 and 39, and frame members 340 and 40, being, preferably, rigidly connected together to form a continuous frame member from the heating means to the end of the cooling means of the mechanism shown in Fig. 14. Means is provided for heating the rollers 127 and 128, comprising electrical heating elements 129 and 130, respectively. Said electrical heating elements are mounted in spaced relation to the walls of the rollers 127 and 128, and electrical insulating material can be provided between said heating elements and the walls of the rollers 127 and 128, if this is found to be desirable.

Each of the rollers 128 is provided with a ring-like contact member 131, with which the conductor 132 leading to the heating elements is connected by means of branches 133, said ring-like members 131 being insulated from the rollers 128 and the stub shafts on the ends thereof, but being electrically connected with one end of the heating element 130 in a well known manner. The other end of each of the heating elements 130 is similarly connected with a conducting ring 131', which is engaged in a similar manner by means of a brush with a conductor to complete the circuit through the heating element. The heating elements 129 are similarly provided with conducting rings 151 engaged by the brushes 152 leading from the conductors 153, said conducting sleeves 151 being insulated from the rollers 127 and the stub shafts thereon, and similar rings 151' are connected with the opposite ends of each of the heating elements 129 and are contacted by brushes similar to the brush 152 to complete the circuit to conductors leading to the other side of the circuit from that from which the conductors 153 extend. Suitable insulating housings 154 and 155 may be provided to enclose the electrical connections. Also any well known thermostatic means may be provided for controlling the temperature of the rollers 127 and 128.

It will be obvious that the electrically heated rollers 127 and 128 will engage the folded paraffin paper or similar material, and that the paraffin will become substantially liquid, or the material will at least become tacky, under such heated condition, as the wrapped packages, wrapped in such paraffin paper, or similar material, will be moved from left to right from the wrapping mechanism toward the cooling mechanism, and that each set of heated rollers will be successively contacted by the folded wrapping material. This will cause such heating of the paraffin that it will become substantially liquefied or the wrapper will be in a tacky condition, depending upon

the form of wrapping material utilized, and as each heated roller will have a rolling contact with the wrapped package, there is no possibility whatsoever of the seals becoming disarranged by engagement with the heating means, as is possible where stationary heated plates are used, and a conveyor, similar to that shown, moves the packages into contact with said plates so that the ends and bottoms thereof are slid along the heated plates.

While only a small number of heating rollers are shown, obviously any desired number can be utilized to get the proper heating effect on the walls of the packages to cause the material that produces the sealing action to be raised to a temperature so as to reach a state that adherence of the layers of wrapping material to each other will take place, due to the combined action of the heating and the cooling means. There is no necessity for halting the movement of the packages as the same move into engagement with the heating means, as is the case with the plate-like members, but if such a halting in engagement with the heating means is desired, the conveyor can be arranged in the usual manner and the loaves pushed one at a time into engagement with the rollers. However, as the rollers will have substantially line contact with the packages, this is not preferred, but a continuous rolling or ironing action on the packages that are being wrapped and sealed is preferred, such as can be obtained with the heated rollers, with a continuously moving wrapped package, such as will be the case in the preferred arrangement of the conveying means, such as shown in Fig. 14. A much longer contact of the heating means with the packages can be maintained where the heating means is in the form of rollers, than where the heating means is in the form of plate-like members, due to the fact that in order to prevent disarrangement of the seals by the flat plate-like members, the packages must be moved into contact therewith, left stationary in such contacting position, and then moved quickly away therefrom, without having such plates form too long a slideway, as it is desirable to reduce the sliding contact between the plates and packages as much as possible to prevent disarrangement of the wrapping material from its properly folded position.

In both the cooling means in the various forms of my invention and the heating means in Figs. 14 to 16, the contact between the packages and the heating or cooling means is a rolling contact, which avoids all relative sliding movement of the surfaces of the packages and members with which the same contact, that would in any manner disarrange the folded wrapping material of the package. Furthermore the cooling is accomplished in all forms of the invention by transfer of heat from the package to the rollers by conduction and is then dissipated by conduction from the rollers, either by the same rolling over members of large mass to dissipate the heat, or through the frame of the machine through the bearings for the rollers, or by a cooling medium with which the rollers come in direct contact, or which passes therethrough, or by contacting walls that are cooled by said cooling medium, by a rolling action over said walls.

What I claim is:

1. In a wrapping machine, sealing means comprising heating means, means engaging each wrapped package with said heating means,

spaced rotatable heat conducting members arranged in a plurality of series, heat dissipating means in heat conducting relation with said heat conducting members, said series being arranged so that rollers in a plurality of said series engage said packages simultaneously, and means for making rolling contact between said package and each of said heat conducting members of each series in succession, and with a plurality of members of each series simultaneously.

2. In a wrapping machine a succession of closely spaced movable heat conducting conveying members successively engaging each wrapped package to hold the wrapping thereof in sealing engagement and conveying said packages from said machine, the contacting surfaces of said heat conducting members and said packages moving at substantially the same speed in the same direction.

3. In a wrapping machine sealing means comprising heating and cooling means with which the wrapped packages engage successively, said cooling means comprising a plurality of series of movable heat conducting members of large mass, the member of each series being arranged in closely spaced side by side relation and means for moving wrapped packages from engagement with said heating means along said plurality of series of members and successively into heat conducting engagement with a plurality of the members of each series, said series being arranged so that members of a plurality thereof are in simultaneous engagement with each package.

4. In a wrapping machine sealing means comprising heating and cooling means with which the wrapped packages engage successively, said cooling means comprising a multiplicity of closely adjacent movable heat extracting members arranged in a plurality of rows, and means for engaging wrapped packages with said heat extracting members of each row in succession, said rows including heat extracting conveying members supporting said packages.

5. In a machine of the character described, a plurality of closely spaced rollers of heat conducting material mounted to freely rotate about horizontal axes and a plurality of closely spaced rollers of heat conducting material mounted to freely rotate about substantially vertical axes.

6. In a machine of the character described, a plurality of closely spaced solid rollers of heat conducting material mounted to freely rotate about horizontal axes and a plurality of closely spaced solid rollers of heat conducting material mounted to freely rotate above said first mentioned rollers about substantially vertical axes, and means for moving wrapped packages into simultaneous rolling heat transfer contact relation to the heat conducting material of a plurality of said rollers rotating about said vertical axes and a plurality of said rollers rotating about said horizontal axes.

7. In a machine of the character described, a plurality of rollers of heat conducting material mounted to rotate about horizontal axes and a plurality of rollers of heat conducting material mounted to rotate about substantially vertical axes, certain of said rollers having heating means therein.

8. In a machine of the character described, a plurality of rollers of heat conducting material mounted to rotate about horizontal axes and a plurality of rollers of heat conducting material mounted to rotate about substantially vertical

axes, certain of said rollers having cooling means therein.

9. In a machine of the character described, a plurality of closely adjacent rollers of heat conducting material mounted to rotate about horizontal axes and a plurality of closely adjacent rollers of heat conducting material mounted to rotate above said first mentioned rollers about substantially vertical axes, means for moving wrapped packages into heat transfer relation to said rollers and means for holding said packages in simultaneous engagement with a plurality of the rollers rotating about said horizontal axes.

10. In a machine of the character described, a plurality of closely adjacent rollers of heat conducting material mounted side by side to rotate about horizontal axes, a plurality of closely adjacent rollers of heat conducting material mounted side by side to rotate about substantially vertical axes, said last mentioned rollers being mounted in spaced rows above the tops of said first mentioned rollers, and means yieldingly urging the rollers of one row for limited movement toward the rollers of the other row.

11. In a machine of the character described, a plurality of solid rollers of heat conducting material mounted in side by side relation to rotate about horizontal axes, a plurality of solid rollers of heat conducting material mounted in side by side relation to rotate about substantially vertical axes, said last mentioned rollers being mounted in spaced rows above said first mentioned rollers, and means for adjusting the spacing of said rows of rollers.

12. In a machine of the character described, a plurality of rollers of heat conducting material mounted in a row in side by side relation to rotate about horizontal axes and a plurality of rollers of heat conducting material mounted in a row in side by side relation to rotate above said first mentioned rollers about substantially vertical axes, and means for moving wrapped packages into heat transfer relation to said rollers and into contacting engagement with successive rollers by gravity.

13. In a machine of the character described, a plurality of rollers of heat conducting material mounted to rotate about horizontal axes, a plurality of rollers of heat conducting material mounted to rotate about substantially vertical axes and means for passing a cooling medium through said rollers.

14. In a wrapping machine, sealing means comprising a plurality of rotatable cooling members, means for successively engaging sealed wrapped packages therewith to progressively cool the seals thereof, heat dissipating means comprising a heat conducting member of large mass mounted in heat conducting relation to the frame of said sealing means, and means for successively engaging said cooling members with said heat conducting member.

15. In a wrapping machine, sealing means comprising a plurality of rotatable cooling members, means for successively engaging sealed wrapped packages therewith to progressively cool the seals thereof, heat dissipating means comprising a heat conducting member having means for receiving cooling medium therein, and means for successively engaging said cooling members with said heat conducting member.

16. In a machine of the character described, a plurality of rollers of heat conducting material mounted to rotate about horizontal axes and a plurality of rollers of heat conducting material

mounted to rotate about substantially vertical axes, said rollers being arranged in endless series and each roller being mounted on a movable axis.

5 17. In a machine of the character described, a plurality of rollers of heat conducting material mounted to rotate about horizontal axes and a plurality of rollers of heat conducting material mounted to rotate about substantially vertical axes, said rollers being arranged in endless series, means connecting the rollers of each series to move the axes of the rollers of each series in unison in a fixed path, heat conducting members with which the rollers of each set successively engage, and means for moving wrapped packages successively into engagement with said rollers.

10 18. In a wrapping machine, sealing means comprising a plurality of heat extracting rollers of heat conducting material mounted to rotate about parallel horizontal axes arranged in a continuous series in close adjacency to support a wrapped package by a plurality thereof at closely adjacent points simultaneously, said series being of a length to successively engage said package with and support said package by a continuously changing grouping of rollers as said package is moved along said series.

15 19. In a wrapping machine, sealing means comprising a plurality of heat extracting rollers of heat conducting material mounted to rotate about parallel horizontal axes arranged in a continuous series in close adjacency to support a wrapped package by a plurality thereof at closely adjacent points simultaneously, said series being of a length to successively engage said package with and support said package by a continuously changing grouping of rollers as said package is moved along said series, and two parallel series of heat extracting rollers mounted above the rollers of said first series, said series being spaced from each other longitudinally of said first mentioned rollers and each of said parallel series comprising a plurality of rollers of heat conducting material mounted to rotate about parallel vertical axes and being in close adjacency to each other to engage a wrapped package with a plurality of rollers of each of said last mentioned series at closely adjacent points simultaneously, each of said last mentioned series being of a length to successively engage said package with a continuously changing grouping of the rollers of each thereof as said package is moved along said last mentioned series.

20 20. In a wrapping machine, sealing means comprising a row of heat extracting rollers of heat conducting material lying side by side and mounted to rotate about parallel horizontal axes arranged in a continuous series to support a wrapped package by a plurality thereof at closely adjacent points simultaneously, said series being of a length to successively engage said package with and support said package by a continuously changing grouping of rollers as said package is moved along said row.

21. In a wrapping machine, sealing means comprising a row of heat extracting rollers of heat conducting material lying side by side and mounted to rotate about parallel horizontal axes arranged in a continuous series to support a wrapped package by a plurality thereof at closely adjacent points simultaneously, said series being of a length to successively engage said package with and support said package by a continuously

19

changing grouping of rollers as said package is moved along said row, and two parallel rows of heat extracting rollers, the rollers of each row lying side by side in a continuous series and both rows being mounted above the rollers of said first row, said parallel rows being spaced from each other longitudinally of said first mentioned rollers and each of said parallel series comprising a plurality of rollers of heat conducting material mounted to rotate about parallel vertical axes, said package engaging with a plurality of rollers of each of said last mentioned series at closely adjacent points simultaneously, each of said last mentioned series being of a length to successively engage said package with a continuously changing grouping of the rollers of each thereof as said package is moved along said rows.

22. In a wrapping machine, sealing means comprising a plurality of rotatable cooling members of heat conducting material, said cooling members being arranged in a plurality of rows and the members of each row being in side by side relation, said rows being positioned so that rollers in a plurality of said rows engage said packages simultaneously, and means for successively engaging sealed packages with the heat conducting surfaces of the members of each row.

23. In a wrapping machine, sealing means comprising a plurality of rotatable cooling members of heat conducting material, said cooling members being arranged in a plurality of rows and the members of each row being in side by side adjacency, said rows being positioned so that rollers in a plurality of said rows engage said packages simultaneously and the rollers of one of said rows support and convey said packages, and means for successively engaging

20

sealed packages with the heat conducting surfaces of the members of each row.

24. In a wrapping machine, sealing means comprising a plurality of rotatable cooling members of heat conducting material, said cooling members being arranged in a plurality of rows and the members of each row being in side by side adjacency, said rows being positioned so that a plurality of rollers in a plurality of said rows engage said packages simultaneously and the rollers of one of said rows support and convey said packages, and means for successively engaging sealed packages with the heat conducting surfaces of the members of each row.
